US0D1086089S

(12) **United States Design Patent** (10) Patent No.: **US D1,086,089 S**
(45) Date of Patent: ** Jul. 29, 2025

(54) **PORTION OF MODULAR LED VIDEO SCREEN**

(71) Applicant: **UNILUMIN GROUP CO., LTD.**, Shenzhen (CN)

(72) Inventors: **Jian Tu**, Guangdong (CN); **Mengxia Jiang**, Guangdong (CN)

(**) Term: **15 Years**

(21) Appl. No.: **35/521,268**

(22) Filed: **Jun. 13, 2023**

(80) **Hague Agreement Data**

Int. Filing Date: **Jun. 13, 2023**

Int. Reg. No.: **DM/230018**

Int. Reg. Date: **Jun. 13, 2023**

Int. Reg. Pub. Date: **Jun. 14, 2024**

(30) **Foreign Application Priority Data**

Dec. 16, 2022 (CN) 202230844251.3

(51) **LOC (15) Cl.** **14-03**

(52) **U.S. Cl.**

USPC **D14/126**; D14/127

Assistant Examiner — Russell Carnell Smith, Jr.

(57) **CLAIM**

The ornamental design for a portion of modular LED video screen as shown and described.

DESCRIPTION

1. Portion of modular LED video screen

1.1 : Perspective

1.2 : Front

1.3 : Back

1.4 : Left

1.5 : Right

1.6 : Top

1.7 : Bottom

1.8 : Perspective

1 Claim, 8 Drawing Sheets
